UNITED STATES PATENT OFFICE.

FELIX ALCAN, OF NEW YORK, N. Y., ASSIGNOR TO THE C. J. PURCELL COMPANY, OF SAME PLACE.

DESIGN FOR A TILE.

SPECIFICATION forming part of Design No. 25,530, dated May 19, 1896.

Application filed February 28, 1896. Serial No. 581,204. Term of patent 14 years.

To all whom it may concern:

Be it known that I, FELIX ALCAN, a citizen of the United States, residing in the city, county, and State of New York, have invented and produced a new and original Design for Tiles, of which the following is a specification, reference being had to the accompanying drawings, forming part thereof.

Figure 1 is a face view of a tile, showing my design; and Fig. 2 is a vertical section thereof taken at the plane of the line $x\ x$, Fig. 1.

The essential feature of my design for the surface of a tile consists in the peripherally-curved three-sided figures A and the curved sinuous stripes B between them.

I claim—

The design for a tile, substantially as shown and described.

FELIX ALCAN.
